UNITED STATES PATENT OFFICE.

EDWARD E. GOLD, OF NEW YORK, N. Y., ASSIGNOR TO GOLD CAR HEATING & LIGHTING COMPANY, A CORPORATION OF NEW YORK.

ELECTROTHERMIC MOTOR FOR THERMOSTATIC SYSTEMS.

1,337,764.

Specification of Letters Patent. Patented Apr. 20, 1920.

Application filed May 2, 1918. Serial No. 232,018.

To all whom it may concern:

Be it known that I, EDWARD E. GOLD, a citizen of the United States of America, residing in the borough of Manhattan, city, county, and State of New York, have invented certain new and useful Improvements in Electrothermic Motors for Thermostatic Systems, of which the following is a specification.

10 My invention relates to that class of devices in which there is employed an electric heater that is thermostatically governed, and in turn controls a thermomotor for operating a valve, damper, or other actuated device for varying the effect of a heating, ventilating, or similar system. The particular purpose of my present invention is to provide an improved form and arrangement of electrical heating unit with reference to the 15 thermomotor, to cause the latter to cool quickly when the electric heater is cut off, thus obtaining prompt action of the thermomotor and a resultant more sensitive operation.

20 A further object of the invention is to adapt such a device especially to governing a fluid valve and provide a simplified arrangement that permits of readily applying such a thermostatic controlling unit to any 25 valve, and readily positioning and assembling the electric conductors and other parts.

The invention is carried out in a general way by employing a supporting base that can be attached to a valve casing and forms 30 a mounting for the entire unit. According to one possible arrangement, the electric heater is mounted upon the upper end of a standard carried by the supporting base, and the heater is positioned upon a support 35 which has vertical openings or other provision permitting the access of upward air currents to the underside of the heating unit. The thermomotor is disposed above the electric heater, preferably in spaced relationship, while under the heater is a terminal support, also provided with vertical air openings and provision for receiving conductors which lead downwardly to a junction box. The latter is arranged on the 40 supporting base under the terminal support, and is preferably of sectional construction to permit it to be removed laterally of the vertical standard that receives the valve stem.

45 To these and other ends the invention con-

sists in certain improvements and combinations of parts, as will be set forth more fully hereinafter and pointed out in the claims at the end of the specification.

In the drawings,—

50 Figure 1 is a vertical sectional view illustrating a preferred arrangement of the invention and showing its application to a fluid valve;

Fig. 2 is a side elevation;

Fig. 3 is a horizontal sectional view on line 3—3 of Fig. 1;

Fig. 4 is a horizontal sectional view on line 4—4 of Fig. 1;

Fig. 5 is a sectional view, showing a 55 slightly different form of heater;

Fig. 6 is a plan view of the heater, and

Fig. 7 is a detail elevation of the baffle-plate which may be used, as in Figs. 5 and 6.

The invention is susceptible of various 75 modifications and applications wherever it is desirable to employ a thermostatically-governed electric heater which controls a thermomotor, the latter coöperating with a valve, damper, or other device to be actuated, and the present disclosure is intended merely by way of example and illustrates a preferred arrangement for governing a fluid valve of a vapor or steam-heating system, in accordance with the temperature of the 80 chamber or room which is heated.

According to this arrangement, A designates a valve casing of usual type having an inlet port B and a controlling valve C which is movable toward and from the seat D 90 which forms a stop for the valve. This structure is similar to that illustrated in my pending application Serial No. 195,501, filed October 9, 1917, and on which the present structure is an improvement. The casing A 95 has an internally-threaded neck A' which receives a filling or adapting member or sleeve E. The latter is threaded exteriorly to fit the casing A and is threaded interiorly to receive a supporting base F, having a 100 threaded extension F' that engages the interior of the sleeve E. The supporting base F carries the entire thermomotor unit, and, by means of an adapting sleeve such as E, can readily be attached to any size of valve 105 casing.

The supporting base F has air inlet openings F³ provided with a vertical hollow standard F² which is arranged centrally and receives the valve stem C'. The latter car- 110

ries a flange or shoulder C², and C³ is a spring arranged between said shoulder and a stuffing box C⁴, and acting normally to elevate the valve stem.

5 G designates a thermomotor, which may be of the usual diaphragm type, and which carries a downward projection G' that engages the upper end of the valve stem C'. The thermomotor G contains a vaporizable

10 liquid and is positioned horizontally, so that such liquid lies on the bottom of the lower wall or diaphragm, and is spread out equally thereover in a shallow pool. The upper wall of the thermomotor is connected to an ad-

15 justable spindle or pin G² which is threaded in a cap or plate H that will be described more fully presently. Thus, by adjusting the spindle G² upwardly or downwardly, as by means of a key or hand-wheel T, the ef-

20 fective movement of the thermomotor upon the valve stem can be varied, and by further turning the wheel T the valve C can be entirely and permanently closed, by downward movement of the thermomotor and valve

25 stem.

The thermomotor G is controlled by an electric heater positioned thereunder, and preferably in spaced relation, in order to permit quick cooling of the heater by cir-

30 culation of air between it and the thermomotor. The heater comprises a resistance coil I which is arranged in a support I' formed of suitable non-conducting and heat-proof material. The support I' has provision for

35 permitting vertical or ascending air currents to strike the underside of the heater or resistance I and pass around all parts of the heater to effectively conduct the heat therefrom and carry the heat to the ther-

40 momotor. This is accomplished in the present embodiment by providing a support I' with a series of vertical openings I² arranged under different parts of the resistance coil I. It will be understood that the

45 resistance unit I is in a circuit which is opened and closed automatically by a thermostat positioned in the chamber or room to be heated, and it is deemed unnecessary for the purposes of this application to make

50 a specific disclosure of this circuit and thermostat, as it may be the same as that shown in my co-pending application already referred to.

The support I' for the electrical heating unit is preferably mounted upon the upper end of the standard F². Arranged under the support I' is a terminal support, preferably in the form of a plate J which rests upon a shoulder J² of the standard F². The plate J is constructed of suitable heat-re-
60 sisting material and has a series of vertical openings J³ to permit free passage of air upwardly, for ventilating and cooling the electric heater. The terminal support J has terminal clips J⁴ which are electrically

connected to the resistance coil I, and receive the conductors K that lead to the thermostat circuit. The conductors K extend through vertical openings in the terminal support J, and pass outwardly 70 through a junction box positioned under the terminal support J. This junction box is preferably of sectional form, comprising two parts L and L' which are arranged upon opposite sides of the central standard 75 F². The sections of the junction box can be positioned and removed laterally with reference to the vertical standard F², and are held in assembled relation by means of bolts L³ and securing nuts L⁴. The conduit or tube K' inclosing the electric cable of conductors K is introduced laterally through the opening K² shown in Fig. 2, and clamped between bosses on the parts L L' of the junction box. The junction box rests 80 upon the base F and preferably extends upwardly until it contacts with the under-surface of the terminal support J. The terminal plate J may be provided with a vertically-extending side wall J⁵ which contacts 85 with the underside of the heater support I' at its outer edge, while above the support I' is a spacing ring M having a top portion M' extending over the thermomotor G and serving as a rest or support for the cap H. 90 The latter is held in place by a series of rods N having bent ends N' engaging in recesses in the upper surface of the plate H. The rods N extend downwardly through the supporting base F and receive at their 95 lower ends securing nuts N², thus clamping in place the terminal support J, the heater support I', and the cap plate H. O designates a casing or side wall surrounding the rods N and having ventilating openings O', 100 while the spacing ring M, which is preferably formed of heat-resisting and non-conducting material, has corresponding openings, permitting the air to find an exit after it has passed upwardly around the thermomotor. The side casing O is held in place by a top casing P which is clamped by a nut Q threaded upon the cap plate H. The air for ventilating the thermomotor enters 110 through openings F³ in the base, passing 115 thence upwardly through openings J³ into contact with all portions of the heater.

The structure described affords an exceedingly practical device that permits of readily positioning the thermomotor unit 120 and connecting the electrical conductors, and it also affords proper means for sufficiently ventilating and cooling the thermomotor when the electrical heating unit is cut off. This is very essential in order 125 that the thermomotor may respond quickly to the actions of the thermostat, as otherwise a constant or reasonably constant temperature cannot be maintained. By the ventilating and cooling system here disclosed, 130

the thermomotor cools very quickly after its heater is cut off, and the resultant valve movement is in close accordance with the operations of the electrical heater.

5 In place of the heater already described, I may use the form illustrated in Figs. 5, 6 and 7. This includes an annular porcelain frame R having recesses or pockets r arranged at opposite points. The frame R 10 rests on a perforate baffle-plate T which is supported by the wall s, and receives coil supporting rods t, having reduced ends u resting in the pockets r. The coils v encircle the rods t which are of porcelain, and 15 are connected to the conductors already described. The supporting rods t are held in place by retaining yokes w.

A heating unit thus constructed permits a free upward circulation of air for cooling 20 and ventilating, and thus affords a quickly responsive action of the thermomotor. Further, the arrangement is economical and durable.

The invention is not confined to the precise arrangement shown, and my purpose 25 may be carried out in other ways without departing from the underlying features of the improvement or the scope of the claims.

What I claim is:—

30 1. The combination with a thermomotor located in a horizontal plane and containing a vaporizable liquid, of an electric heater located beneath said motor, and a support for the heater provided with vertical openings 35 permitting air to pass upwardly from below into contact with the underside of and through the heater.

2. The combination with a thermomotor located in a horizontal plane and containing a vaporizable liquid, of an electric heater 40 located beneath said motor in spaced relation thereto, and a support for the heater provided with vertical openings permitting air to pass upwardly from below into contact with the underside of and through the heater.

3. The combination with a thermomotor located in a horizontal plane and containing a vaporizable liquid, of an electric heater 50 located beneath the motor and supported by means which permits air currents to travel upwardly from below into contact with the underside of and through the heater.

55 4. The combination with a thermomotor located in a horizontal plane and containing a vaporizable liquid, of an electric heater located beneath the motor in spaced relation thereto and supported by means which 60 permits air to reach the underside of the heater by traveling upwardly from below.

5. The combination with a body portion and an actuated member movable therein, of an adapting sleeve removably engaging 65 said body portion, supporting means re-

movably mounted on the sleeve, and a thermomotor mounted upon the supporting means and connected to the actuated member.

6. The combination with a body portion 70 and an actuated member movable therein, of an adapting sleeve in threaded engagement with the body portion, a supporting base in threaded engagement with said sleeve, and a thermomotor mounted on the supporting 75 base and connected to the actuated member.

7. The combination with a supporting base, of an actuated member extending through the base, a thermomotor coöperating with the actuated member, an electric 80 heater positioned beneath the thermomotor, a sectional junction box surrounding the actuated member and removably positioned beneath said heater, and conductors leading from the junction box to the heater. 85

8. The combination with a supporting base including a vertical hollow standard, of an actuated member extending through the base, a thermomotor coöperating with the actuated member, an electric heater positioned beneath the thermomotor, a sectional junction box which is removable or 90 positionable laterally with respect to said standard, and conductors leading from the junction box to the heater. 95

9. The combination with a supporting base, of an actuated member extending through the base, a thermomotor coöperating with the actuated member, an electric heater positioned beneath the thermomotor, 100 a terminal support arranged beneath the heater, a sectional junction box removably positioned under the terminal support and surrounding the actuated member, and conductors leading from said junction box to 105 the terminal support.

10. The combination with a supporting base including a vertical hollow standard, of an actuated member extending through the standard, a thermomotor coöperating with the actuated member, an electric heater positioned beneath the thermomotor and mounted on said standard, a terminal support arranged on said standard under the heater, a sectional junction box positioned 110 under the terminal support upon said supporting base and removable laterally of the standard, and conductors leading from the junction box to the terminal support. 115

11. The combination with a supporting 120 base including a vertical hollow standard, of an actuated member extending through the standard, a thermomotor coöperating with the actuated member, an electric heater positioned beneath the thermomotor, a support for the heater having vertical openings which permit free upward movement 125 of air currents into contact with the under surface of the heater, a terminal support arranged beneath the heater and having 130

openings to permit the upward travel of air therethrough, a sectional junction box located under the terminal support and removable laterally of said standard, and conductors leading from the junction box to the terminal support.

12. The combination with a supporting base including a vertical hollow standard, of an actuated member extending through 10 the standard, a thermomotor coöperating with the actuated member; an electric heater positioned under the thermomotor and spaced therefrom, a terminal support arranged beneath the heater in spaced relation, a junction box located beneath the terminal support, a cap above the thermomotor, spacing means positioned between said cap, heater, terminal support and supporting base respectively, and retaining devices connecting said supporting base and cap and holding the parts in assembled relationship.

13. The combination with a thermomotor containing a vaporizable liquid, of an electric heater positioned beneath the thermomotor comprising a frame having oppositely arranged recesses, supporting rods resting in said recesses, resistance coils arranged on said rods, and a member connected to and governed by the thermomotor. 25

14. The combination with a thermomotor containing a vaporizable liquid, of an electric heater positioned beneath the thermomotor comprising an annular frame having opposite recesses or pockets, resistance supporting rods with their ends resting in said pockets, resistance coils arranged on the rods, and a member connected to and governed by the thermomotor. 30 35

In witness whereof I have hereunto signed my name.

EDWARD E. GOLD.
